UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 18, 1921, Serial No. 478,473. Renewed May 11, 1927.

This invention relates to mining machines. It has for an object to provide improved variable speed mechanism for actuating the feeding means of a mining machine, said mechanism being of simple and compact construction and arrangement and combining an increased range of variable speed control with a material reduction of the number of necessary moving parts. Another object of 10 of the invention is to provide improved devices for controlling the variable speed feed actuating mechanism, said devices being of such a character as to permit of convenient operation and being self-retaining in all of 15 their positions of adjustment. A further object of the invention is to provide improved means whereby a mining machine feed actuating mechanism may be employed to propel the truck on which the machine is transported from place to place, said means being easily and quickly engageable with or disengageable from the cooperating devices on the truck when the machine is loaded or unloaded, and including no parts on the machine which are idle when the machine is 20 performing its cutting operation, or which project from the outline of said machine and tend to impede such operation. A still further object of the invention is to provide improved means for guiding the flexible feeding member employed in connection with mining machines of certain types, whereby the parts are rendered more compact and convenient of operation, and 25 whereby the range of adaptability of the machine and of the feeding mechanism thereof is increased.

The foregoing and other objects of the invention, together with means whereby the 40 same may be carried into effect, will best be understood from the following description of one form or embodiment thereof illustrated in the accompanying drawings, in which,—

Fig. 1 is a side elevation, partially broken away, of the complete machine and the truck upon which it is mounted.

Fig. 2 is a plan view thereof.

Fig. 3 is a slightly enlarged rear elevation of the machine removed from the truck.

Fig. 4 is a further enlarged vertical section of the rear end of the machine, taken substantially on the line 4—4 of Fig. 3, cer-

tain parts being omitted in order to facilitate the illustration. 55

Fig. 5 is a section partially in elevation taken substantially on the lines 5—5 of Figs. 3 and 6, showing the controlling devices for the friction clutches.

Fig. 6 is a fragmentary elevation of an upper portion of the rear of the machine, showing the operating handle for the friction clutch controlling device. 60

Fig. 7 is an enlarged plan view of the rear end of the machine. 65

Fig. 8 is a further enlarged fragmentary elevation of one of the lower rear corners of the machine, showing one of the movable guide members.

Figs. 9 and 10 are diagrammatic views 70 illustrating the operation of the machine in room and pillar work.

Figs. 11 and 12 are diagrammatic plan views of the apparatus in use as a longwall machine. 75

Figs. 13 and 14 are rear elevations illustrating the arrangement of the flexible feeding member during the operations of the machine illustrated in Figs. 9 and 10 respectively. 80

The mining machine is shown in Figs. 1 and 2 as mounted on a truck comprising a body 20 mounted on wheels 21 adapted to run on a suitable track 22. The axles 23 of the wheels 21 are provided with sprockets 24 which are connected by drive chains 25, one of said axles being provided with additional sprockets 26 connected by chains 27 with sprockets 28 on a propelling shaft 29 extending transversely of the truck body 90 and journaled in uprights or brackets 30 bolted or otherwise secured thereto. The shaft 29 is provided intermediate its ends with a bevel gear 31 which meshes with a bevel pinion 32 journaled in a transverse truck frame member 33, said pinion 32 having means, hereinafter described, for operatively connecting the same with a moving part of the mining machine when the latter is loaded, whereby said pinion may be rotated and, through the connections above described, operate to propel the truck. 95

The mining machine proper shown herein is of the general type disclosed and claimed in my application for Letters Patent filed December 26, 1919, Serial No. 347,571. This 100 105

machine comprises a casing 34 having at its forward end a head 35 in which is mounted to swing about a vertically disposed pivot 36 a cutter bar 37 provided with a cutter chain 38. Herein, the cutter bar is adapted to be adjusted about the axis of the pivot 36 into the longitudinal position shown or into various angular positions with respect to the longitudinal axis of the machine, being 5 locked in its several adjusted positions by means of a removable pin 39 adapted to engage registering openings 40 in said bar and head. The machine, when unloaded from the truck, is fed along the mine face by a flexible 10 feeding member, usually a cable or chain, which passes about suitably arranged rotary guide members (hereinafter more fully described) at the rear end of the machine and cooperates with a rotary feed operating 15 member herein shown as located at the rear end of the machine and disposed with its axis horizontal, as in my prior application for Letters Patent filed June 5, 1919, Serial No. 301,917. As in my application Serial No. 20 347,571, above referred to, the machine is herein shown as provided with an auxiliary rotary guide member 129 carried by a detachable bracket 41 secured to the head 35 by means of a suitable bolt which may be 25 engaged with any of the openings 40 in said head, thereby permitting attachment of said bracket to said head at either side of the latter.

The cutter chain 38 is actuated, through 30 the usual connections under the control of a clutch lever 43, by an electric or other motor M having a driving pinion 47' for the cutting mechanism and the usual controller 44, said motor also supplying the power for 35 actuating the feed operating member 42. In accordance with the present invention, reversible variable speed transmission mechanism is interposed between said motor and feed operating member, said mechanism 40 being adapted to rotate said member at either of two speeds in one direction or at either of two speeds in the opposite direction, the driving speeds in one direction being relatively higher than those in the opposite direction. To these ends, as herein shown, the 45 following construction is provided.

Referring to Fig. 4, the motor shaft 45 has keyed thereon a sleeve 46 journaled in an antifriction bearing 46^a in the machine 50 frame and provided at its end with a preferably integral pinion 47 which meshes with coaxially disposed external and internal gears 48 and 49, respectively, thereby driving said gears in opposite directions and at 55 different speeds. The gear 48 is rotatably mounted on a main transmission shaft 50 journaled adjacent one end in a suitably disposed frame member 51 and at its opposite end in a sleeve 52 to which the feed operating member 42 is keyed, said sleeve and

member being rotatably mounted in antifriction bearings 53 and 54 carried by the end of the casing 34. The internal gear 49 is provided with a hub 55 which is rotatably mounted in an antifriction bearing 56 carried by the frame member 51. The external and internal gears 48 and 49 are adapted to be alternately connected with the shaft 50, so as to rotate the latter, by means of oppositely disposed, multiple-disc friction 70 clutches 57 and 58, respectively, said clutches having a common, centrally disposed pressure member 59 connected with said shaft for rotation therewith by means of a transverse pin 60. The shaft 50 is hollow, and the pin 60 passes through longitudinally disposed slots 61 therein and engages a transverse aperture in a rod 62 guided for longitudinal movement in said shaft and by which the pressure member 59 may be operated to cause 75 either of the gears 48 or 49 to be operatively connected with the shaft 50 through the corresponding clutch 57 or 58. The rod 62 extends coaxially through the sleeve 52 and feed operating member 42 to the outer side 80 of the latter and is operated by a hand wheel 63 having attached thereto, as by screws 64, a sleeve 65 in threaded engagement with the outer end 66 of the sleeve 52. The feed operating member 42 is formed with an axial counterbore or recess to receive the sleeve 65 between which and the walls of said recess is preferably interposed a bushing 67 also in threaded engagement with the end 66 of the sleeve 52. The sleeve 65 is formed with an 85 internal shoulder 68 between which and the hub of the hand wheel 63 is interposed an antifriction bearing 69 held also between a flange 70 on the rod 62 and a collar 71 secured to the end of said rod by a nut 72, whereby said rod and hand wheel are connected for axial or longitudinal movement in unison while permitting free rotation 90 thereof.

From the foregoing it will be seen that 95 rotation of the hand wheel 63 in one direction or the other, and consequent turning of the sleeve 65 on the threaded end of the sleeve 52, will result in a longitudinal movement of the rod 62 inwardly or outwardly 100 in accordance with the direction of rotation of said hand wheel. Inward movement of the rod 62 will result in the operative engagement of the clutch 57 to connect the relatively small external gear 48 with the 105 shaft 50, thereby causing said shaft to be driven from the pinion 47 at a relatively high speed in one direction, while outward movement of said rod 62 will result in the operative engagement of the clutch 58 to 110 connect the relatively large internal gear 49 with the shaft 50, thereby causing said shaft to be driven from the pinion 47 at a relatively low speed in the opposite direction. It will also be seen that, by operation of the 115

hand wheel 63, the clutches 57 and 58 may be engaged with any desired degree of pressure which, due to the threaded engagement of the sleeve 65 with the sleeve 52, will be automatically maintained.

Rotation of the shaft 50 is transmitted to the feed operating member 42 to rotate the latter in one direction or the other, depending upon the direction of rotation of said shaft, by mechanism which is adjustable to produce a relatively high or a relatively low speed of rotation of said member with respect to the speed of rotation of said shaft which, as above described, is relatively high in one direction and relatively low in the opposite direction. Herein, this mechanism includes a single counter-shaft 73 journaled at one end in the frame member 51 and having keyed to its opposite end a hub 74 mounted in an antifriction bearing 75 carried by the end of the casing 34. The countershaft 73 is disposed parallel to the main transmission shaft 50 above the same and with its axis in substantially the same vertical plane with the axis of said shaft 50. The hub 74 carries a preferably integral pinion 76 which meshes with a gear 77 secured, as by cap screws 78, to a flange 79 on the sleeve 52, whereby the feed operating member 42, which is keyed to said sleeve, is driven from the countershaft 73 which, in turn, may be driven at relatively high or relatively low speed through alternatively operative connections with the shaft 50. As shown, said connections comprise a pinion 80 fast on the shaft 50 and meshing with a gear 81 keyed to a hub 82 rotatably mounted on the countershaft 73. The gear 81 is adapted for connection, through a multiple-disc friction clutch 83, with a hub 84 keyed to the shaft 73, whereby, when said clutch is engaged, said countershaft 73 will be driven from the shaft 50 through the pinion 80 and gear 81 at a relatively high speed. The hub 82 carries a preferably integral pinion 85 which meshes with a gear 86 secured, as by cap screws 87, to a hub 88 rotatably mounted on the shaft 50. The hub 88 is formed with clutch teeth to engage cooperating clutch teeth on a second hub 89 also rotatably mounted on the shaft 50 and carrying a preferably integral pinion 90. The pinion 90 meshes with a gear 91 adapted for connection, through a multiple-disc friction clutch 92, with a hub 93 keyed to the counter-shaft 73 whereby, when said clutch is engaged, said countershaft will be driven from the shaft 50, through the gears 80, 81, 85, 86, 90 and 91, at a relatively low speed.

It will be observed that the transmission mechanism above described, while permitting a wide range of variable speed control, is of extremely compact arrangement, permitting the longitudinal dimensions of the machine to be materially shortened: an im-

portant consideration in machines of this type whose availability for use in many places is limited by their size. It will also be noted that the axis of rotation of all of the moving parts of the mechanism lie in the same substantially vertical plane, thereby reducing the space, laterally of the casing, required for their accommodation therein, and permitting the positioning at the sides of the transmission mechanism, of the various electrical apparatus employed in machines of this character and the placing of which, without increasing the overall dimensions of the machine, has heretofore presented a difficult problem.

The clutches 83 and 92, in addition to controlling the speed of rotation of the feed operating member 42 with respect to the shaft 50, serve as yielding transmission elements whereby the power transmitted to said feed operating member may be limited in order to prevent excessive strain upon the mechanism in the event of abnormal resistance to the machine, as when an unusually hard spot or other obstruction is unexpectedly encountered. To this end said clutches are engaged by springs 94 interposed between the hubs 84 and 93 and collars 95 and 96 slidably mounted on said hubs respectively, said collars having annular grooves which are engaged by the outer ends of pressure levers 97 pivoted at 98 to the respective hubs and engaging the clutch discs. Each of the springs 94 abuts at one end against a plug or bushing 99 in threaded engagement with the corresponding hub 84 or 93, whereby the clutch engaging pressure exerted by said springs through the levers 97 may be adjusted.

In order to render the clutches 83 and 92 alternatively operative for the purpose of causing the feed operating member 42 to be driven from the shaft 50 at high or low speed, as above explained, the following mechanism is provided. The ends of the sleeves 95 and 96 are engaged by rollers 100 (see Fig. 5) carried by bifurcated arms of bell crank levers 101 and 102, respectively, pivoted at 103 to suitably disposed ears 104 formed on the casing 34, said levers being adapted to force said sleeves inwardly in opposition to the springs 94 to release the respective clutches. The levers 101 and 102 are herein also provided at their ends opposite the rollers 100 with rollers 105 which cooperate with cam lugs or projections 106 and 107 formed on a sliding cam bar 108 guided for longitudinal movement in suitable guides formed on the casing 34 and in the ears 104 thereof. The cam lugs 106 and 107 are so located on the cam bar 108 that, when said cam bar is moved into the longitudinal position shown in Fig. 5, the lug 107 will operate the lever 102 to force the sleeve 96 inwardly and release the clutch 92,

the lug 106 at this time releasing the lever 101 and permitting the sleeve 95 to be operated by its springs 94 to engage the clutch 83. When, however, the cam bar 108 is moved longitudinally toward the right from the position shown in Fig. 5, the cam lug 106 will operate the lever 101 to force inwardly the sleeve 95 and release the clutch 83, the lug 107 at the same time releasing the lever 102 and permitting engagement of the clutch 92 by its springs 94. The cam lugs 106 and 107 are formed with longitudinally disposed surfaces 109 which are engaged by the rollers 105 when the latter are forced by said lugs into their clutch releasing positions in opposition to the springs 94, the re-action of said rollers against said surfaces having no tendency to move the cam bar 108, which is therefore self-retained in adjusted position. For positively operating said cam bar in order to adjust the mechanism, said bar is provided, outside the casing 34, with an operating handle 110. Although, as above explained, the bar 108 is self-retained in adjusted position, said handle 110 may, if desired, be pivotally mounted upon the end of said bar and provided with lugs 111 adapted when said handle is turned into one angular position to pass through slots or notches 112 in the casing 34, and when said handle is turned into another angular position to engage the inner or outer sides of said casing, depending upon the longitudinal position of the cam bar, thereby locking said cam bar in such position against longitudinal movement to shift the clutches.

The pinion 32 (Figs. 1 and 2) for actuating the truck propelling shaft 29 is connected by a universal joint 113 with a coupling member 114 adapted, when the mining machine is loaded upon the truck, to be operatively connected with a moving part of the feed actuating mechanism in order that the power for operating the truck propelling mechanism may be supplied by the motor of the machine. To this end, said coupling member 114 and the hub 74 which, as above explained, constitutes one of the elements of the actuating mechanism for the feed operating member 42, are formed with or as cooperating clutch elements or members. In the construction shown, the outer end of the hub 74 is formed with a square socket 115 (Figs. 3, 4, and 6) adapted to receive the squared end of the coupling member 114. Said socket 115 is located entirely within the outline of the machine casing 34, although readily accessible from the exterior thereof for purposes of engagement by the coupling member 114, so as to afford no projecting parts which might be in the way when the machine is performing its cutting operation. It will be seen that, by arranging the transmission element 74 for connec-

tion with the truck propelling mechanism, not only is the special gearing or other connecting mechanism usually employed for this purpose (which gearing or other mechanism is preferably idle during the cutting operation) eliminated, thereby simplifying the construction, but, since the hub 74 is an element of the regular transmission mechanism for actuating the feed operating member 42, the truck drive can be readily controlled by the device for controlling the feed, thereby eliminating any special controlling device for this purpose.

Referring to Fig. 3, it will be noted that the rear end of the machine is provided, in addition to the feed operating member 42, whose axis of rotation, as above explained, is horizontally and longitudinally disposed, with a pair of similarly disposed rotary guide members 116 and 117 arranged above the feed operating member 42 and at opposite sides thereof respectively. The flexible feeding member is herein shown as a chain 118 and the feed operating and guide members as sprockets adapted to cooperate therewith. This chain 118 passes about the feed operating member or sprocket 42, about one or the other of the guide members or sprockets 116 or 117 according to the direction of movement of the machine, as hereinafter explained, and also about one or the other of a plurality of guide members or sprockets 119 and 120 arranged respectively below the guide members or sprockets 117 or 116, the axes of rotation of said sprockets 119 and 120 being vertically disposed. The rear end of said machine is further provided with an auxiliary rotary guide member or sprocket 121 disposed upon an axis transverse to the horizontal longitudinal axes of the guide members or sprockets 116 and 117 and inclined to the vertical axes of the guide members or sprockets 119 and 120, said guide member 121, as herein shown, being journaled in a bracket 122 secured to the rear end of the casing 34 between the feed operating member 42 and the guide member 117. The auxiliary guide member 121 may be conveniently employed for the purpose of loading the machine upon the truck, the flexible feeding member 118 being at that time passed about the vertical guide member 119, thence about the feed operating member 42, thence about the guide members 116 and 117, and finally about the auxiliary guide member 121 from which it may be led to the usual chain fork 121' or other suitable fixed abutment upon the truck body 20.

The vertical guide members or sprockets 119 and 120, which are disposed at the lower rear corners of the casing 34, are arranged to be received and housed in recesses 123 formed in said casing at these points. These members, in the construction shown, are mounted upon studs 124 (see particularly

Fig. 8) which are supported at their upper ends by and depend from short arms 125 pivoted, as by screw studs 126, to lugs or supports 127 projecting horizontally from the casing 34, whereby said guide members may be swung outwardly into the position shown in Fig. 8 and in full lines at the right in Fig. 7, or may be swung inwardly into the recesses 123 as shown in Fig. 3 and in full lines at the left in Fig. 7. The positions of said members in the recesses 123 are fixed by stop lugs 128 projecting into said recesses and adapted to engage the arms 125 when the latter are swung inwardly.

15 It will be observed by reference to Fig. 7 that, by reason of the horizontal disposition of the axes of the feed operating member 42 and guide members 116 and 117, the portions or surfaces of these members which receive the flexible feeding member may be disposed substantially in or be intersected by a common vertical plane lying relatively close to the rear end of the machine and indicated by the broken line A in Fig. 7, thereby providing an extremely compact arrangement. The axes of the members 119 and 120 being vertical, or transverse to the axes of the members 42, 116 and 117, it is desirable, in order to prevent cramping or binding of the 20 flexible feeding member, that the peripheral guide portions or surfaces of said members 119 and 120 be substantially tangential to the vertical plane above referred to. The housing of said members 119 and 120 in the recesses 123 permits said members to be tangential to said plane at the inner side thereof, notwithstanding the proximity of said plane to the rear end of the machine, while the movable mounting of said members permits them to be swung outwardly into positions tangential to said plane at the outer side thereof. It will therefore be seen that the portion of the flexible feeding member 118 extending between the feed operating member 42 and either of the guide members 119 and 120 may lie in the same vertical plane as the portion of said member between the feed operating member and the guide members 116 and 117 (see also Fig. 3) and 25 may engage said guide members 119 and 120 either externally or internally depending upon the requirements imposed by the direction of pull or re-action of said flexible member upon the machine, as will hereinbelow be apparent.

In room and pillar work, the cutter bar 37 is swung into its longitudinal position, as shown in Figs. 9 and 10, and is locked in such position by the locking pin 39. The machine is then preferably sumped longitudinally into the face in a well known manner by extending the flexible feeding member longitudinally of the machine between the same and the adjacent rib to a suitable anchor adjacent the face, i. e. as indi-

cated in dotted lines in Figs. 9 and 10, and then operating the feed operating member 42 to draw in that portion. In order to cut toward the left, as shown in Fig. 9, the flexible feeding member 118 is anchored at 70 its forward end at the left end of the mine face, passes about the guide member 129 carried by the bracket 41, which at this time is secured to the left side of the head of the machine, said flexible feeding member passing from said guide member 129 longitudinally of the machine at the left side thereof, thence about the outer side of the guide member 120, which at this time is housed in its recess 123, thence 75 (see Fig. 13) about the feed operating member 42, about the guide member 117, which serves to hold said flexible feeding member in engagement with said feed operating member, and then under the member 116 to 80 the right hand rib in a usual manner. In order to cut toward the right, as shown in Fig. 10, the flexible feeding member will be oppositely arranged, as shown in said figure and in Fig. 14, and as will be clear 85 without further explanation.

The use of the machine in longwall cutting is illustrated in Figs. 11 and 12. For this purpose the cutter bar 37 is swung into a position transverse to the machine at one 90 side or the other thereof in accordance with the direction of cut, as will be familiar to those skilled in the art, an abutment 130 herein being carried by the cutter bar and adapted to have the flexible feeding member connected thereto in such manner that when the flexible member is drawn in by the feed operating member 42, the bar will be swung about its pivot into its desired laterally extending position wherein it may be 95 locked by the pin 39. In cutting toward the right as shown in Fig. 11, the flexible feeding member 118 is anchored at its right end, passes about the inner side of the guide member 119, which at this time is swung 100 outwardly, thence about the feed operating member 42, and finally about the guide member 116, as shown in Fig. 14, it being understood that during such cutting the slack portion of the chain may if desired be laid 105 over the guide member 117 with its free end trailing at the side of the machine as shown in Fig. 11. In cutting toward the left as 110 shown in Fig. 12, the flexible feeding member 118 will be oppositely disposed, as will 115 be clear without further explanation.

It will thus be seen that, by reason of the horizontal longitudinal arrangement of the feed operating member 42 and guide members 116 and 117, the flexible feeding 120 member 118 can be readily engaged therewith or disengaged therefrom and re-engaged in a different manner, as illustrated in Figs. 13 and 14. It will also be seen that, by reason of the movable mounting 125

of said guide members 119 and 120, said members may be readily so disposed as to permit the engagement of the flexible feeding member therewith either externally thereof, as shown in Figs. 9 and 10, or internally thereof as in case of the members 119 and 120 in Figs. 11 and 12, respectively, depending upon the bearing or reaction of the flexible feeding member upon said guide members, thereby facilitating the adaptation of the machine to either long-wall or room and pillar work. It will further be seen that the feed operating member and the several guide members are, in each case supported at one side or end only, the opposite side being unobstructed, so that, in arranging the flexible feeding member, it may be passed freely across the axes of the feed operating and guide members and about the latter without threading it through the machine. These and other advantages of the invention will, however, be apparent to those skilled in the art without further explanation.

While I have herein shown and described in detail one form which the invention may assume in practice and several ways in which it may be used, it will be understood that the particular constructions, arrangements and uses described and shown have been chosen for illustrative purposes merely, and that the invention may be otherwise embodied and practiced without departing from its spirit or the scope of the claims hereunto appended.

What I claim as new and desire to secure by Letters Patent is:

1. In a mining machine, the combination with a feed operating member adapted to cooperate directly with flexible feeding means and rotatable upon an axis disposed longitudinally of the machine, of actuating means therefor including a motor, a longitudinally disposed transmission shaft, variable speed transmission mechanism between said shaft and motor, and variable speed transmission mechanism between said shaft and said member.

2. In a mining machine, the combination with a feed operating member adapted to cooperate directly with flexible feeding means and rotatable upon an axis disposed longitudinally of the machine, of actuating means therefor including a motor, a transmission shaft disposed coaxially with said member, variable speed transmission mechanism between said shaft and motor, and variable speed transmission mechanism between said shaft and member.

3. In a mining machine, the combination with cutting mechanism including a cutter bar and feeding mechanism including a feed operating member adapted to cooperate directly with flexible feeding means and rotatable upon an axis disposed longitudinally

of the machine and located on the opposite end thereof from said bar, of actuating means for said member including a transmission shaft disposed coaxially therewith and rotatable with respect thereto, and means for driving said member from said shaft.

4. In a mining machine, the combination with a frame, cutting mechanism thereon including a cutter bar, and feeding mechanism including a feed operating member adapted to cooperate directly with flexible feeding means and journaled in said frame and disposed at the opposite end thereof from said bar with its axis longitudinal of said machine, of actuating means for said member including a longitudinal shaft journaled at one end in said frame and at its opposite end in said member, and means for driving said member from said shaft.

5. In a mining machine, the combination with cutting mechanism including a cutter bar and feeding mechanism including a feed operating member adapted to cooperate directly with flexible feeding means and rotatable on an axis disposed longitudinally of said machine and located at the opposite end thereof from said bar, of mechanism for actuating said member comprising a main transmission shaft disposed longitudinally of said machine and a single countershaft disposed parallel to said transmission shaft and operatively connected therewith and with said member.

6. In a mining machine, the combination with a feed operating member adapted to cooperate directly with flexible feeding means and rotatable upon an axis disposed longitudinally of said machine and substantially coincident with the longitudinal center line of the latter, of mechanism for actuating said member comprising a longitudinally disposed transmission shaft, a single countershaft disposed parallel to said transmission shaft and operatively connected with said member, and variable speed gearing connecting said shafts.

7. In a mining machine, the combination with a feed operating member adapted to cooperate directly with flexible feeding means and rotatable on an axis extending longitudinally of said machine, of mechanism for actuating the same comprising a main transmission shaft and a single countershaft operatively connected therewith and with said member, said main shaft and countershaft having their axes disposed substantially in a common longitudinal vertical plane.

8. In a mining machine, the combination with a feed operating member adapted to cooperate directly with flexible feeding means and rotatable on an axis disposed longitudinally of said machine, of mechanism for actuating the same comprising a

- longitudinally extending motor shaft, a transmission shaft forming a continuation of said motor shaft and operatively connected with said member, and variable speed 5 gearing connecting said shafts.
9. In a mining machine, the combination with a feed operating member adapted to cooperate directly with flexible feeding means and rotatable on an axis disposed longitudinally of said machine, of mechanism for actuating the same comprising a longitudinally extending motor shaft, a transmission shaft forming a continuation of said motor shaft and operatively connected with 10 said member, and reversing gearing connecting said shafts.
10. In a mining machine, the combination with a feed operating member adapted to cooperate directly with flexible feeding 20 means, of mechanism for actuating the same comprising a longitudinally extending motor shaft, a transmission shaft forming a continuation of said motor shaft and operatively connected with said member, and variable speed reversing gearing connecting 25 said shafts.
11. In a mining machine, the combination with a feed operating member rotatable upon an axis disposed longitudinally of said 30 machine, of mechanism for actuating said member comprising a motor shaft, a longitudinally disposed transmission shaft, variable speed gearing connecting said shafts, and variable speed transmission mechanism between said transmission shaft and member.
12. In a mining machine, the combination with a feed operating member adapted to cooperate directly with flexible feeding means and rotatable on an axis disposed longitudinally of said machine, of mechanism 40 for actuating the same comprising a longitudinally extending motor shaft, a main transmission shaft forming a continuation of said motor shaft, variable speed gearing connecting said shafts, and a single countershaft disposed parallel to said transmission shaft and operatively connected therewith and with said member.
13. In a mining machine, the combination with a feed operating member, of mechanism 50 for actuating the same comprising a motor shaft provided with a pinion, a transmission shaft operatively connected with said member, and internal and external gears on said transmission shaft meshing with said pinion.
14. In a mining machine, the combination with a feed operating member adapted to cooperate directly with flexible feeding 60 means and rotatable on an axis extending longitudinally of the machine, of mechanism for actuating the same comprising a longitudinal motor shaft, a longitudinal transmission shaft, a plurality of transmission shafts for operatively connecting said shafts.
- carried thereon, and alternatively operative clutches for connecting said elements respectively to one of said shafts.
15. In a mining machine, the combination with a feed operating member adapted to 70 cooperate directly with flexible feeding means and rotatable on an axis disposed in a plane extending longitudinally of the machine, of mechanism for actuating the same comprising a motor shaft, a transmission shaft, variable speed gearing connecting said shafts, a countershaft operatively connected with said member, and variable speed gearing connecting said transmission shaft and countershaft.
16. In a mining machine, the combination with a feed operating member adapted to 75 cooperate directly with a flexible feeding member in feeding said mining machine during cutting and rotatable on an axis disposed in a plane extending longitudinally of the machine, of mechanism for actuating the same comprising a main transmission shaft, a countershaft operatively connected with said member and extending longitudinally of the machine, a plurality of transmission elements for operatively connecting said main transmission shaft and countershaft, and alternatively operative clutches on said countershaft for connecting said elements respectively with one of said shafts.
17. In a mining machine, the combination with a feed operating member adapted to 85 cooperate directly with flexible feeding means, of mechanism for actuating the same comprising a motor shaft, a transmission shaft, a plurality of transmission elements for operatively connecting said shafts, alternatively operative clutches for connecting said elements respectively with one of said shafts, a countershaft operatively connected with said feed operating member, a plurality of transmission elements for operatively connecting said transmission shaft and countershaft, and alternatively operative friction clutches for connecting said last named elements respectively with one of said last named shafts.
18. In a mining machine, the combination with flexible feeding mechanism including a feed operating member adapted to cooperate directly with flexible feeding means and rotatable on an axis disposed in a plane extending longitudinally of the machine, of mechanism for actuating the same comprising a main transmission shaft, a countershaft operatively connected with said member and extending longitudinally of the machine, a plurality of transmission elements for operatively connecting said transmission shaft and countershaft, and alternatively operative friction clutches on said countershaft for connecting said elements respectively with one of said shafts.
19. In a mining machine, the combination

with flexible feeding mechanism including a feed operating member rotatable on an axis lying in a plane extending longitudinally of the machine, of mechanism for actuating the same comprising a main transmission shaft, a countershaft operatively connected with said member and extending longitudinally of the machine, and direct and speed reducing gearing operatively connecting said shafts, said speed reducing gearing including a plurality of elements coaxial with each of said shafts.

20. The combination with a truck having propelling means, of a separable bottom cutting mining machine carried by said truck, said mining machine having a feed operating member adapted to cooperate directly with flexible feeding means and rotatable on an axis lying in a plane extending longitudinally of the machine and mechanism for actuating said feed operating member comprising a main transmission shaft, a countershaft connected with said member, and direct and speed reducing gearing operatively connecting said shafts, said gearing including an element for operating said truck propelling means.

21. In a mining machine, in combination, a frame, a feed operating member adapted to cooperate directly with flexible feeding means, and mechanism for actuating said member comprising a main transmission shaft, a countershaft, a member carried by said countershaft and journaled in said frame for directly operatively connecting said countershaft and member, and variable speed gearing connecting said transmission shaft and countershaft.

22. The combination with a truck having propelling means, of a mining machine carried by said truck, said mining machine having a feed operating member adapted to cooperate directly with flexible feeding means and mechanism for actuating the same comprising a main transmission shaft, a countershaft, a member carried by said countershaft and journaled in said frame for operating said truck propelling means and for directly operatively connecting said countershaft with said operating member, and variable speed gearing connecting said transmission shaft and countershaft.

23. In a mining machine, in combination, a frame, a feed operating member adapted to cooperate directly with flexible feeding means and journaled in said frame and disposed with its axis longitudinal of said machine, and mechanism for actuating said feed operating member comprising a longitudinally disposed transmission shaft journaled at one end in said frame and at its opposite end in said member, a countershaft, an element carried by said countershaft and journaled in said frame for operatively connecting said countershaft and said operat-

ing member, and variable speed gearing connecting said transmission shaft and countershaft.

24. In a mining machine, the combination with a feed operating member adapted to cooperate directly with flexible feeding means, of mechanism for actuating the same including a shaft arranged parallel with a line parallel with the axis of rotation of said feed operating member, transmission elements thereon, alternatively operative clutches for connecting said elements and shaft, a rod longitudinally movable in said shaft for controlling said clutches, and a manually operable member for operating said rod.

25. In a mining machine, the combination with a feed operating member adapted to cooperate directly with flexible feeding means, of mechanism for actuating the same including a shaft, transmission elements thereon, alternatively operative clutches for connecting said elements and shaft, a rod movable longitudinally in said shaft for controlling said clutches, a longitudinally fixed sleeve disposed coaxially with said shaft and rod, a manually operable member having threaded engagement with said sleeve, and an antifriction bearing connecting said member and rod.

26. In a mining machine, the combination with a feed operating member adapted to cooperate directly with flexible feeding means and rotatable on an axis extending longitudinally of the machine, of mechanism for actuating the same comprising a motor shaft, a transmission shaft, a plurality of transmission elements for operatively connecting said shafts, alternatively operative clutches for connecting said elements respectively with one of said shafts, a countershaft operatively connected to said feed operating member, a plurality of transmission elements for operatively connecting said transmission shaft and countershaft, a plurality of clutch devices for connecting said last named elements respectively with one of said last named shafts, and means for rendering said last named clutch devices alternatively operative.

27. The combination with a truck having propelling means, of a mining machine carried by said truck and adapted to cut upon the mine bottom, said mining machine having means for operating said propelling means and including a member rotating on a horizontal axis extending longitudinally of said machine and housed within the outline of said machine but engageable by said propelling means when said machine is loaded on said truck.

28. The combination with a truck having propelling means, of a mining machine carried by said truck and adapted to cut upon the mine bottom, said mining machine hav-

ing a motor including a shaft, a feed operating member adapted to cooperate directly with flexible feeding means, and means driven by said shaft for actuating said member including an element rotatable on a horizontal axis extending longitudinally of the machine and engageable with the propelling means on said truck when said machine is loaded thereon for actuating said propelling 10 means.

29. The combination with a truck having propelling means, of a mining machine carried by said truck and having cutting mechanism, said mining machine having a casing 15 adapted to slide upon the mine bottom, a feed operating member thereon adapted to cooperate directly with flexible feeding means, and means for actuating said feed operating member peculiar thereto as regards cutting mechanism actuation including an element within said casing but engageable therein by said propelling means when said machine is loaded on said truck for actuating said propelling means.

25 30. The combination with a truck having propelling means, of a mining machine carried by said truck and adapted to slide upon the mine bottom, said mining machine having a motor including a shaft, a feed operating member adapted to cooperate directly with flexible feeding means, and means driven by said shaft for actuating said member including an element having a permanent connection with said feed operating 30 member and rotating on a horizontal axis extending longitudinally of the machine and engageable by said propelling means to actuate the same when said machine is loaded on said truck.

40 31. The combination with a truck having propelling means comprising a plurality of cooperating elements, of a mining machine carried by said truck and adapted to slide upon the mine bottom, said mining machine having a motor including a shaft, cutting mechanism, a feed operating member adapted to cooperate directly with flexible feeding means, and means driven by said shaft for actuating said member peculiar thereto 45 as regards cutting mechanism actuation, and cooperating clutch members on one of the elements of said feed actuating means and one of the elements of said truck propelling means and automatically operably engageable by machine movement when said machine is loaded on said truck.

32. The combination with a truck having propelling means comprising a plurality of cooperating elements, of a mining machine carried by said truck and adapted to slide upon the mine bottom, said mining machine having a motor including a shaft, cutting mechanism, a feed operating member adapted to cooperate directly with flexible feeding 60 means, and means driven by said shaft

for actuating said member peculiar thereto as regards cutting mechanism actuation and including an element having permanent connection with said feed operating member, and cooperating clutch members on one of the elements of said feed actuating means and one of the elements of said truck propelling means and automatically operably engageable by machine movement when said machine is loaded on said truck. 70

33. The combination with a truck having a propelling shaft and means for actuating said shaft, of a mining machine carried by said truck and adapted to slide upon the mine bottom, said mining machine having a motor including a shaft, cutting mechanism, a feed operating member adapted to cooperate directly with flexible feeding means, and means driven by said motor for actuating said member and as regards cutting mechanism actuation peculiar to the actuation of said member and including an element engageable with said propelling shaft actuating means when said machine is loaded on said truck. 75

34. The combination with a truck having a propelling shaft and means for actuating said shaft, of a mining machine carried by said truck and adapted to slide upon the mine bottom, said mining machine having a motor including a shaft, a feed operating member adapted to cooperate directly with flexible feeding means, and means driven by said shaft for actuating said member, and cooperating clutch members each rotatable on a horizontal longitudinally extending axis on one of the elements of said feed actuating means and on said propelling shaft actuating means respectively, said clutch members being engageable when said machine is loaded on said truck. 80

35. The combination with a truck having propelling means, of a mining machine carried by said truck adapted to slide upon the mine bottom, said mining machine having a feed operating member adapted to cooperate directly with flexible feeding means and means for actuating the same, a member for actuating said propelling means, a member engageable with one of the elements of said feed actuating means when said machine is loaded on said truck, and a universal joint connecting said last named members. 110

36. In a mining machine, feeding means including a flexible feeding member, a feed operating member rotatable at a cutting speed upon a horizontal axis disposed longitudinally of said machine, rotatable guide members at opposite sides of the rear end of said machine adapted to cooperate with said flexible feeding member, and a stationary guide member for said flexible feeding member, said last mentioned guide member being rotatable upon an inclined axis lying 115 120 125

in a plane to which the axis of said rotatable feed operating member is perpendicular.

37. In a mining machine, feeding means including a flexible feeding member, a feed operating member rotatable at a cutting speed upon a horizontal axis disposed longitudinally of said machine, rotatable guide members at opposite sides of the rear end of said machine adapted to cooperate with said flexible feeding member, and a stationary guide member for said flexible feeding member, said last mentioned guide member being nearer said feed operating member than said previously mentioned guide members and being rotatable upon an inclined axis lying in a plane to which the axis of said rotatable feed operating member is perpendicular.

38. In a mining machine, cutting mechanism at one end thereof, and feeding means at the opposite end thereof including a flexible feeding member and guide members cooperating therewith and at said end, one of said guide members being movable bodily on said machine to permit engagement thereof by said flexible feeding member at either side thereof.

39. In a mining machine, a machine frame, cutting mechanism at one end thereof, and feeding means including a flexible feeding member, a feed operating member rotatable upon a horizontal axis extending longitudinally of the machine at the end of the frame remote from the cutting mechanism, a guide member cooperating directly therewith and rotatable upon an axis lying in a plane to which the axis of said feed operating member is perpendicular, a swinging arm by which said guide member is carried, and a stop for limiting the movement of said arm.

40. In a mining machine, the combination with a casing having a recess, of feeding means including a flexible feeding member and a rotatable guide member therefor housed in said recess and movable into an operative position outside the same.

41. In a mining machine, the combination with a casing having a recess, of feeding means including a flexible feeding member and a guide member cooperating therewith, said guide member being adjustable into or out of said recess.

42. In a mining machine, feeding means comprising a flexible feeding member, a feed operating member cooperating with said flexible feeding member and disposed with its axis horizontal and parallel to the major dimension of the machine, and a plurality of rotary guide members for said flexible feeding member also disposed with their axes horizontal and arranged respectively above and at opposite sides of said feed operating member.

43. In a mining machine, feeding means

comprising a flexible feeding member, a feed operating member cooperating with said flexible feeding member and disposed with its axis horizontal, a plurality of guide members for said flexible feeding member also disposed with their axes horizontal and arranged above and at opposite sides respectively of said feed operating member, and a plurality of rotary guide members disposed with their axes vertical and arranged respectively below said first named guide members.

44. In a mining machine, the combination with a frame having a horizontally extending support, of feeding mechanism including a flexible feeding member, a swinging guide member therefor beneath said support, and a vertically disposed pivot for said guide member depending from said support and carried solely thereby.

45. In a mining machine, feeding means including a flexible feeding member and feed operating and guide elements having surfaces engaged by said flexible feeding member, one of said elements being movable into operative guiding positions at opposite sides of a plane passing through the aforesaid surfaces on the other of said elements while remaining connected to the machine.

46. In a mining machine, feeding means including a flexible feeding member, feed operating and guide members rotatably mounted on substantially horizontal axes, said members having surfaces engaged by said flexible feeding member and lying substantially in a common vertical plane, and a guide member rotatably mounted on a vertical axis movable into different operative guiding positions at either side of said plane.

47. In a mining machine, the combination with a casing having a recess, of feeding means including a flexible feeding member, feed operating and guide members mounted on said casing to rotate about substantially parallel horizontal axes, said members having surfaces engaged by said flexible feeding member and lying substantially in a common vertical transverse plane, and a guide member housed in said recess and lying adjacent said plane.

48. In a mining machine, the combination with a casing having a recess, of feeding means including a flexible feeding member, feed operating and guide members mounted on the rear end of said casing to rotate about substantially horizontal axes, said members having surfaces engaged by said flexible feeding member and lying substantially in a common vertical plane, and a guide member mounted in said recess to rotate about a substantially vertical axis and lying adjacent said plane.

49. In a mining machine, the combination with a casing having a recess, of feeding means including a flexible feeding member,

- feed operating and guide members mounted on said casing to rotate about substantially parallel axes, said members having surfaces engaged by said flexible feeding member and 5 lying substantially in a common plane to which said axes are perpendicular, and a guide member mounted to rotate about an axis transverse to said first named axes, said last named member being movable into and 10 out of said recess into operative guiding positions at opposite sides of said plane. 15
50. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite 20 end thereof from said cutting mechanism, and driving mechanism for said member comprising transmission elements all of which rotate on axes parallel to a line parallel to the axis of said feed operating member and which effect drive of said feed operating member at a cutting speed. 25
51. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite 30 end thereof from said cutting mechanism, and driving mechanism for said member comprising transmission elements all of which rotate on axes parallel to a line parallel to the axis of said feed operating member 35 and which effect drive of said feed operating member at a cutting speed, a plurality of said transmission elements being coaxial with said feed operating member. 40
52. The combination with a flexibly fed laterally movable mining machine slideable on a mine bottom and having cutting mechanism projecting from one end of its body, of a feed operating member adapted to cooperate directly with flexible feeding means 45 and rotatable on an axis disposed longitudinally of the machine body at the opposite end thereof from said cutting mechanism, and driving mechanism for said member comprising transmission elements all of 50 which rotate on axes parallel to a line parallel to the axis of said feed operating member and which effect drive of said feed operating member at a cutting speed, said transmission elements including a longitudinally 55 extending shaft disposed coaxially with said member. 60
53. The combination with a flexibly fed laterally movable mining machine slideable on a mine bottom and having cutting mechanism projecting from one end of its body, of 65
- a feed operating member adapted to cooperate directly with flexible feeding means and rotatable on an axis disposed longitudinally of the machine body at the opposite end thereof from said cutting mechanism, and mechanism for driving said feed operating member at a cutting speed including a plurality of cooperating transmission elements all of which are rotatable about longitudinally extending axes lying in a single vertical plane. 70
54. The combination with a flexibly fed laterally movable mining machine slideable on a mine bottom having cutting mechanism projecting from one end of its body, of a feed operating member adapted to cooperate directly with flexible feeding means and rotatable on an axis disposed longitudinally of the machine body at the opposite end thereof from said cutting mechanism, and driving mechanism including a plurality of cooperating transmission elements rotatable about a plurality of parallel longitudinally extending shafts whose several axes lie in a single plane and which together support 75 all of said transmission elements. 80
55. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite 85 end thereof from said cutting mechanism, and driving mechanism for said member including a plurality of friction devices each disposed on a longitudinal axis. 90
56. The combination with a flexibly fed laterally movable mining machine slideable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and driving mechanism for said member including a longitudinal shaft and a plurality of friction devices 100 thereon. 105
57. The combination with a flexibly fed laterally movable mining machine slideable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and fast and slow speed driving connections for said member 110 including a plurality of friction devices 115
58. The combination with a flexibly fed laterally movable mining machine slideable on a mine bottom and having cutting mechanism projecting from one end of its body, of 120
59. The combination with a flexibly fed laterally movable mining machine slideable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and fast and slow speed driving connections for said member 125 including a plurality of friction devices 130

each disposed on a longitudinal axis and controlling a different feed.

58. The combination with a flexibly fed laterally movable mining machine slidable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, fast and slow speed driving connections for said member including a longitudinal shaft and fast and slow speed friction devices thereon, and reduction mechanism between said shaft and feed operating member including a member rotatable on an axis parallel to the axis of the latter.

59. The combination with a flexibly fed laterally movable mining machine slidable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, fast and slow speed driving connections for said member including a longitudinal shaft and fast and slow speed friction devices thereon, and reduction mechanism between said shaft and feed operating member including a pinion rotatable on an axis parallel to the axis of the latter and a larger meshing gear rotatable with the latter.

60. The combination with a flexibly fed laterally movable mining machine slidable on a mine bottom and having cutting mechanism projecting from one end of its body, of a feed operating member adapted to operate directly with flexible feeding means and rotatable on an axis disposed longitudinally of the machine body at the opposite end thereof from said cutting mechanism, and driving connections for said member including a motor having a shaft, a longitudinal transmission shaft operatively connected to said member, an internal gear rotatable with said shaft, and a pinion driving said internal gear and driven by said motor shaft.

61. The combination with a flexibly fed laterally movable mining machine slidable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a motor having a shaft, a longitudi-

nal transmission shaft operatively connected to said member, an internal gear rotatable with said shaft, a pinion driving said internal gear and driven by said motor shaft, and a friction clutch controlling the connection of said internal gear to said shaft.

62. The combination with a flexibly fed laterally movable mining machine slidable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including an internal gear, a motor driven driving pinion therefor, and a plurality of trains of transmission mechanism between said internal gear and feed operating mem- 85

ber.

63. The combination with a flexibly fed laterally movable mining machine slidable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and driving connections for said member including a motor driven pinion, a larger gear meshing therewith and disposed on a parallel axis, and a plurality of trains 100 of transmission mechanism between said larger gear and feed operating member.

64. The combination with a flexibly fed laterally movable mining machine slidable on a mine bottom and having cutting mechanism projecting from one end of its body, of a feed operating member rotatable on an axis disposed longitudinally of the machine body at the opposite end thereof from said cutting mechanism and adapted to cooperate 105 with a flexible feeding member in moving said machine bodily during cutting in the direction of cutting, and driving connections for said member including an internal gear, a motor driven driving pinion therefor, and variable speed transmission mechanism between said internal gear and feed operating member.

65. The combination with a flexibly fed laterally movable mining machine slidable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and driving connections for said member including a motor 120

- driven pinion, a larger gear meshing therewith and disposed on a parallel axis, and variable speed transmission mechanism between said larger gear and feed operating member.
66. The combination with a flexibly fed laterally movable mining machine slideable on a mine bottom and having cutting mechanism projecting from one end of its body, of a feed operating member rotatable on an axis disposed longitudinally of the machine body at the opposite end thereof from said cutting mechanism and adapted to cooperate with a flexible feeding member in moving said machine bodily during cutting in the direction of cutting, and driving connections for said member including a motor driven member rotatable on a longitudinal axis, a larger meshing member rotatable on a parallel axis, and variable speed transmission mechanism between said larger member and said feed operating member.
67. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a motor driven element rotatable on a longitudinal axis, a cooperating second element of different size rotatable on a parallel axis, and variable speed transmission mechanism between said element and said feed operating member.
68. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a motor driven element rotatable on a longitudinal axis, a cooperating second element of different size rotatable on a parallel axis, and variable speed transmission mechanism between said second mentioned element and said feed operating member having certain common speed reduction connections thereto for each speed.
69. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a motor driven element rotatable on a longitudinal axis, a cooperating second element of different size rotatable on a parallel axis, and variable speed transmission mechanism between said second mentioned element and said feed operating member having certain common speed reduction connections thereto for each speed.
70. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a motor driven element rotatable on a longitudinal axis, a cooperating second element of different size rotatable on a parallel axis, and variable speed transmission gearing between said second mentioned element and said feed operating member having friction mechanism included therein.
71. The combination with a flexibly fed laterally movable mining machine slideable on a mine bottom and having cutting mechanism projecting from one end of its body, of a feed operating member adapted to cooperate directly with flexible feeding means and rotatable on an axis disposed longitudinally of the machine body at the opposite end thereof from said cutting mechanism, and driving connections for said member including a plurality of sets of reduction mechanism each including different sized elements rotatable on parallel longitudinal axes and variable speed transmission mechanism between said sets of elements.
72. The combination with a mining machine slideable laterally on a mine bottom and having flexible feeding means including a flexible feeding member, of cutting mechanism projecting from one end thereof, feed operating mechanism including a feed operating member rotatable on an axis extending longitudinally of the machine body at the opposite end thereof from said cutting mechanism, and a guide member disposed on an axis perpendicular to a line parallel to the axis of said feed operating member and with its pitch circle tangent to a line tangent to the pitch circle of said feed operating member.
73. The combination with a mining machine slideable laterally on a mine bottom and having flexible feeding means including a flexible feeding member, of cutting mechanism projecting from one end thereof, feed operating mechanism including a feed operating member rotatable on an axis extending longitudinally of the machine body at the opposite end thereof from said cutting mechanism.

anism, and a plurality of guide members disposed at each side of said feed operating member and so disposed relative to the latter that their pitch circles are tangent to lines tangent to the pitch circle of said feed operating member.

74. The combination with a mining machine slideable laterally on a mine bottom and having flexible feeding mechanism including a flexible feeding member, of kerf cutting mechanism projecting from one end thereof, feed operating mechanism including a feed operating member rotatable on an axis extending longitudinally of the machine body at the opposite end thereof from said cutting mechanism, and a guide member disposed on an axis perpendicular to the axis of said feed operating member, said members being so disposed that a horizontal line disposed between the planes which include the surfaces at the top and bottom of the kerf cut by the machine may be tangent to the pitch circles of each of said members.

75. The combination with a mining machine slideable laterally on a mine bottom and having flexible feeding mechanism including a flexible feeding member, of cutting mechanism projecting from one end thereof, feed operating mechanism including a feed operating member rotatable on an axis extending longitudinally of the machine body at the opposite end thereof from said cutting mechanism, and a plurality of guide members disposed on opposite sides of said feed operating member on axes perpendicular to lines parallel to a line parallel to the axis of the said feed operating member, said feed operating and guiding members being so disposed as to permit said flexible member to remain on said feed operating member and a guiding member when passed directly from said feed operating member to either of the guide members, while permitting said flexible member to act in a plane adjacent the mine bottom.

76. The combination with a mining machine slideable laterally on a mine bottom and having flexible feeding mechanism including a flexible feeding member, of cutting mechanism projecting from one end thereof, feed operating mechanism including a feed operating member rotatable on an axis extending longitudinally of the machine body at the opposite end thereof from said cutting mechanism, a guide member disposed on an axis perpendicular to a line parallel to a line parallel to the axis of said feed operating member, said members being so disposed as to permit said flexible member to remain on said members when passed directly from one to the other while permitting said flexible member to act in a plane adjacent the mine bottom, and a supplemental guiding means for directing said flexible

member longitudinally of the machine adjacent the machine center line.

77. The combination with a mining machine slideable laterally on a mine bottom and having flexible feeding mechanism including a flexible feeding member, of cutting mechanism projecting from one end thereof, feed operating mechanism including a feed operating member rotatable on an axis extending longitudinally of the machine body at the opposite end thereof from said cutting mechanism, a plurality of guide members disposed on opposite sides of said feed operating member on axes perpendicular to lines parallel to a line parallel to the axis of said feed operating member, said feed operating and guiding members being so disposed as to permit said flexible member to remain on said feed operating and a guiding member when passed directly from said feed operating member to either of said guide members, while permitting said flexible member to act in a plane adjacent the mine bottom, and a supplemental guiding means for directing said flexible member longitudinally of the machine adjacent the machine center line.

78. The combination with a flexibly fed mining machine slideable laterally on a mine bottom and having cutting mechanism projecting from one end thereof, of feed operating mechanism including a feed operating member adapted to cooperate directly with flexible feeding means and rotatable on an axis extending longitudinally of the machine body at the opposite end thereof from said cutting mechanism, and truck driving mechanism thereon including a truck driving member driven by a moving part rotatable with one of said mechanisms.

79. The combination with a mining machine slideable on a mine bottom, cutting mechanism including a cutter bar disposed longitudinally of the machine body, and flexible feeding mechanism including flexible feeding portions extending in opposite directions from opposite ends of the machine body and operative to draw in one portion while the other is lengthened including a feed operating member rotatable on an axis disposed longitudinally of said body and at the opposite end thereof from the cutting portion of said bar and operative on rotation to draw in the portion extending from the front end of the machine.

80. The combination with a mining machine slideable on a mine bottom, cutting mechanism including a cutter bar disposed longitudinally of the machine body, and flexible feeding mechanism for feeding said bar into and laterally in either direction along a face including flexible feeding portions extending in opposite directions from opposite ends of the machine body and operative to draw in one portion while the other

is lengthened including a feed operating member rotatable on an axis disposed longitudinally of said body and at the opposite end thereof from the cutting portion 5 of said bar and operative on rotation to draw in the portion extending from the front end of the machine.

81. The combination with a mining machine 10 slideable on a mine bottom and having cutting mechanism including a cutter bar pivoted at one end of the machine body and adjustable into longitudinal or lateral positions, of flexible feeding mechanism for feeding said bar into a face and laterally 15 along the same when said bar is either longitudinally or laterally disposed including a feed operating member rotatable on an axis disposed on an axis extending longitudinally of said body and at the opposite 20 end thereof from the cutter bar pivot.

82. The combination with a mining machine slideable on a mine bottom and having cutting mechanism including a cutter bar pivoted at one end of the machine body 25 and adjustable into longitudinal or lateral positions, of flexible feeding mechanism for feeding said bar into a face and laterally along the same in either direction when said bar is either longitudinally or laterally disposed 30 including a feed operating member disposed on an axis extending longitudinally of said body and at the opposite end thereof from the cutter bar pivot and adapted to cooperate directly with flexible 35 feeding means.

83. The combination with a mining machine slideable on a mine bottom and having a cutter bar projecting from one end thereof, of flexible feeding mechanism for feeding 40 said machine into and laterally along a coal face including a feed operating member adapted to cooperate directly with flexible feeding means and disposed at the opposite end of said machine from said bar, and driving 45 mechanism therefor including a motor driven pinion rotatable on a longitudinal axis, a meshing internal gear rotatable on a longitudinal axis, and variable speed mechanism between said internal gear and said 50 feed operating member.

84. The combination with a mining machine having a projecting cutting bar and a feed operating member at the other end of said machine from said bar and adapted 55 to cooperate directly with a flexible feeding member and rotatable on an axis extending longitudinally of said machine, of a guiding member rotatable on a relatively perpendicular axis disposed at one side of a vertical 60 longitudinal plane extending through the axis of said feed operating member and adapted to receive a flexible feeding member passing directly from said feed operating member.

85. The combination with a mining ma-

chine having a projecting cutting bar and a feed operating member at the other end of said machine from said bar and adapted to cooperate directly with a flexible feeding member and rotatable on an axis extending 70 longitudinally of said machine, of a guiding member rotatable on a relatively perpendicular axis disposed at one side of a vertical longitudinal plane extending through the axis of said feed operating member and adapted to receive a flexible feeding member passing directly from said feed operating member, the axis of said guiding member being disposed at one corner of said machine. 75

86. The combination with a mining machine having a projecting cutting bar and a feed operating member at the other end of said machine from said bar and adapted to cooperate directly with a flexible feeding member and rotatable on an axis extending longitudinally of said machine, of a guiding member rotatable on a relatively perpendicular axis at one side of a vertical longitudinal plane extending through the axis of said feed operating member and adapted to receive a flexible feeding member passing directly from said feed operating member, said guide member being so disposed that a plane perpendicular to the guiding surface of said member is substantially tangential to said feed operating member. 80

87. The combination with a mining machine having a projecting cutting bar and a feed operating member at the other end of said machine from said bar and adapted to cooperate directly with a flexible feeding member and rotatable on an axis extending longitudinally of said machine, of a guiding member rotatable on a vertical axis at 100 one side of a vertical longitudinal plane extending through the axis of said feed operating member and adapted to receive a flexible feeding member passing directly from the under side of said feed operating member, said guide member being so disposed that a plane perpendicular to the guiding surface of said member is substantially tangential to said feed operating member. 105

88. In a longwall mining machine having a pivoted cutter bar, the combination with a feed operating member adapted to cooperate directly with a flexible feeding member and rotatable upon an axis parallel to the path of movement of the machine during longwall 110 cutting, of actuating means therefor including a motor, a transmission shaft parallel to the axis of said feed operating member, variable speed transmission mechanism between said shaft and motor, and variable 115 transmission mechanism between said shaft and said member. 120

89. In a longwall mining machine having a pivoted cutter bar, the combination with a feed operating member adapted to cooperate 125

130

directly with a flexible feeding member and rotatable upon an axis lying in a vertical plane parallel to the path of movement of the machine during longwall cutting, of actuating means therefor including a motor, a transmission shaft parallel to said plane, variable speed transmission mechanism between said shaft and motor, and variable speed transmission mechanism between said shaft and said member.

90. In a longwall mining machine having a pivoted cutter bar, the combination with a feed operating member adapted to cooperate directly with a flexible feeding member and rotatable upon an axis parallel to the path of movement of the machine during longwall cutting, of actuating means therefor including a motor, and variable speed transmission mechanism between said motor and member including a transmission shaft parallel to the axis of said feed operating member.

91. In a longwall mining machine having a pivoted cutter bar, the combination with a feed operating member adapted to cooperate directly with a flexible feeding member and rotatable upon an axis lying in a vertical plane parallel to the path of movement of the machine during longwall cutting, of actuating means therefor including a motor, and variable speed transmission mechanism between said motor and member including a transmission shaft parallel to said plane and rotating on a horizontal axis.

92. In a mining machine, the combination with a machine frame carrying cutting mechanism at one end thereof, of feeding mechanism including a feed operating member adapted to cooperate directly with flexible feeding means and rotatable upon an axis disposed longitudinally of the machine and located at the opposite end of said frame from said cutting mechanism, and actuating mechanism for said feed operating member including a transmission shaft disposed coaxially therewith and rotatable with respect thereto but constituting a driving member therefor, means for driving said member from said shaft, and means for driving said shaft at a plurality of predetermined speeds.

93. In a mining machine, the combination with a frame carrying cutting mechanism at one end thereof, of feeding mechanism including a feed operating member adapted to cooperate directly with flexible feeding means and rotatable upon a longitudinally extending axis at the opposite end of said frame, and actuating mechanism for said member comprising a transmission shaft coaxial with said feed operating member and means for effecting rotation of said feed operating member at different speeds including plural speed reduction gearing all of whose elements rotate on axes parallel to a line parallel to the axis of said shaft.

94. In a mining machine, the combination

with a frame supporting at one end thereof cutting mechanism, of feeding mechanism including a feed operating member adapted to cooperate directly with flexible feeding means and rotatable upon an axis extending longitudinally of the machine at the opposite end of said machine frame from said cutting mechanism, and actuating means therefor including a shaft coaxial with said feed operating member and a plurality of gears coaxial therewith and driven at different speeds, and means for frictionally connecting said gears selectively thereto.

95. In a mining machine, the combination with a frame carrying cutting mechanism at one end thereof, of feeding mechanism including a feed operating member adapted to cooperate directly with flexible feeding means and rotatable on an axis extending longitudinally of the machine and at the opposite end of said frame from said cutting mechanism, and actuating means for said feed operating member effective to cause rotation thereof at different speeds including a shaft coaxial with said feed operating member, a plurality of gears rotatable coaxially with said shaft and selectively connectible thereto, a plurality of gears rotating coaxially with each other upon axes parallel to the axis of said shaft, and a plurality of clutches coaxial with said shaft.

96. In a mining machine, the combination with a feed operating member adapted to cooperate directly with flexible feeding means and rotatable on an axis disposed longitudinally of the machine, of mechanism for actuating the same comprising a longitudinally extending motor shaft, a transmission shaft operatively connected to said member and disposed with its axis in the same longitudinally extending vertical plane as the axis of the motor shaft, variable speed gearing connecting said shafts, and speed reducing mechanism connecting said transmission shaft and member.

97. In a mining machine, the combination with a feed operating member adapted to cooperate directly with flexible feeding means and rotatable on an axis disposed longitudinally of the machine, of mechanism for actuating the same comprising a longitudinally extending motor shaft, a transmission shaft operatively connected to said member and disposed with its axis in the same longitudinally extending vertical plane as the axis of said motor shaft, reversing gearing connecting said shafts, and speed reducing mechanism connecting said transmission shaft and member.

98. In a mining machine, the combination with a feed operating member adapted to cooperate directly with flexible feeding means and rotatable on an axis disposed longitudinally of the machine, of mecha-

- nism for actuating the same comprising a longitudinally extending motor shaft, a transmission shaft operatively connected to said member and disposed with its axis in the same longitudinally extending vertical plane as the axis of said motor shaft, variable speed reversing gearing connecting said shafts, and speed reducing mechanism connecting said transmission shaft and member.
- 10 99. The combination with a truck having propelling means, of a separable bottom cutting mining machine carried by said truck, said mining machine having a feed operating member adapted to cooperate directly with flexible feeding means and rotating on an axis lying in a plane extending longitudinally of the machine and mechanism for actuating said feed operating member comprising a main transmission shaft, a countershaft connected with said member, direct and speed reducing gearing operatively connecting said shafts, and truck propelling means including an element coaxial with one of said shafts.
- 15 100. The combination with a truck having propelling means, of a separable bottom cutting mining machine carried by said truck, said mining machine having a feed operating member adapted to cooperate directly with flexible feeding means and rotating on an axis lying in a plane extending longitudinally of the machine and mechanism for actuating said feed operating member comprising a main transmission shaft, a countershaft connected with said member, direct and speed reducing gearing operatively connecting said shafts, and truck propelling means including an element coaxial with and rotatable by one of said shafts.
- 20 101. The combination with a truck having propelling means, of a self-contained mining machine of a type adapted to cut upon a mine bottom carried by said truck, said mining machine having a feed operating member adapted to cooperate directly with flexible feeding means and rotatable on a horizontal axis extending longitudinally thereof, and mechanism for actuating said feed operating member comprising a main transmission shaft in alinement with said feed operating member, a driving motor, means for effecting rotation of said shaft at a plurality of predetermined speeds while said motor speed remains constant, operative connections between said shaft and said feed operating member, and a truck driving member driven by said shaft and rotatable on a longitudinally extending horizontal axis.
- 25 102. The combination, in a flexibly fed mining machine slidable over a mine bottom during cutting including a machine frame having cutting mechanism projecting from one end thereof, of feeding mechanism including a feed operating member rotatable at a cutting speed upon a horizontal axis extending longitudinally of the machine frame at the opposite end of said machine frame from said cutting mechanism, flexible feeding means cooperating therewith, and guiding means for said flexible feeding means including guiding members rotating upon vertical axes at opposite sides of the central vertical plane of said machine frame and having their pitch circles tangent to a line tangent to the pitch circle of said feed operating member.
- 30 103. The combination, in a flexibly fed mining machine slidable over a mine bottom during cutting, including a machine frame having cutting mechanism projecting from one end thereof and feeding mechanism including a feed operating member rotatable at a cutting speed upon a horizontal axis extending longitudinally of the machine frame at the opposite end of said machine frame from said cutting mechanism, flexible feeding means cooperating therewith, and guiding means for said flexible feeding means including at each side of the central longitudinal vertical plane of said machine a pair of guiding members each of which is so disposed that a line tangent to its pitch circle may be tangent to the pitch circle of said feed operating member.
- 35 104. The combination, in a flexibly fed mining machine slidable over a mine bottom during cutting including a machine frame having cutting mechanism projecting from one end thereof and feeding mechanism including a feed operating member rotatable upon a horizontal axis extending longitudinally of the machine at the opposite end of said machine frame from said cutting mechanism, flexible feeding means cooperating therewith, and guiding means for said flexible feeding means including guiding members at opposite sides of the central longitudinal vertical plane of said frame rotatable on vertical axes disposed nearer the last mentioned end of the machine frame than said feed operating member and having their pitch circles tangent to a single straight line tangent to the pitch circle of said feed operating member.
- 40 105. The combination, in a flexibly fed mining machine slidable over a mine bottom during cutting including a machine frame having cutting mechanism projecting from one end thereof and feeding mechanism including a feed operating member rotatable upon a horizontal axis extending longitudinally of the machine at the opposite end of said machine frame from said cutting mechanism, flexible feeding means cooperating therewith, and guiding means for said flexible feeding means including guiding members at opposite sides of the central longitudinal vertical plane of said frame rotatable on vertical axes disposed nearer the last mentioned end of the machine frame than

said feed operating member and having their pitch circles tangent to a single straight line tangent to the pitch circle of said feed operating member at the lower side of the latter.

5 106. Mining apparatus including a frame supporting at one end thereof cutting mechanism, a driving member rotatable upon a horizontal axis extending longitudinally of said frame and at the end thereof remote from said cutting mechanism, mechanism operatively connectible therewith and actuatable thereby to effect propulsion of said apparatus in a path parallel to the major dimension of said frame, and driving means 10 for said cutting mechanism and said member including a common driving motor disposed between said cutting mechanism and said member and having a power shaft parallel to the axis of rotation of said member, 15 and driving connections between said motor and cutting mechanism and between said motor and member, said latter driving connection including reversing mechanism and having all the elements thereof rotating on 20 horizontal longitudinally extending axes.

107. Mining apparatus including a frame supporting at one end thereof cutting mechanism, a driving member rotatable upon a horizontal axis extending longitudinally of said frame and at the end thereof remote from said cutting mechanism, mechanism operatively connectible therewith and actuatable thereby to effect propulsion of said apparatus in a path parallel to the major dimension of said frame, and driving means 30 for said cutting mechanism and said member including a common driving motor disposed between said cutting mechanism and said member and having a power shaft parallel to the axis of rotation of said member, and driving connections between said motor and cutting mechanism and between said motor and member, said latter driving connection including plural predetermined speed 35 driving mechanism and having all the elements thereof rotating on horizontal longitudinally extending axes.

108. Mining apparatus including a frame supporting at one end thereof cutting mechanism, a driving member rotatable upon a horizontal axis extending longitudinally of said frame and at the end thereof remote from said cutting mechanism, mechanism operatively connectible therewith and actuatable thereby to effect propulsion of said apparatus in a path parallel to the major dimension of said frame, and driving means 50 for said cutting mechanism and said member including a common driving motor disposed between said cutting mechanism and said member and having a power shaft parallel to the axis of rotation of said member, and driving connections between said motor and cutting mechanism and between said 55 motor and member, said latter driving con-

nexion including plural predetermined speed driving and reversing mechanism and having all the elements thereof rotating on horizontal longitudinally extending axes.

109. The combination with a mining machine having a body slidable on a mine bottom, cutting mechanism including a pivoted cutter bar disposed longitudinally of the body, and flexible feeding mechanism including flexible feeding portions extending in opposite directions from opposite ends of the machine body and operative to draw in one portion while the other is lengthened including a feed operating member disposed on a horizontal axis and at the opposite end 70 of the machine body from the cutting portion of said bar.

110. The combination with a mining machine having a body slidable on a mine bottom, cutting mechanism including a pivoted cutter bar disposed longitudinally of the machine body, and flexible feeding mechanism for feeding said bar into and laterally in either direction along a face including flexible feeding portions extending in 85 opposite directions from opposite ends of the machine body and operative to draw in one portion while the other is lengthened including a feed operating member disposed on a horizontal axis and at the opposite end 90 of the machine body from the cutting portion of said bar.

111. The combination with a mining machine having a body slidable on the mine bottom and having cutting mechanism including a cutter bar pivoted at one end of the machine body and adjustable into longitudinal or lateral positions, of flexible feeding mechanism for feeding said bar into a face and laterally along the same when said bar is either longitudinally or laterally disposed including a feed operating member disposed on a horizontal axis and at the opposite end of the machine body from the cutter bar pivot.

112. The combination with a mining machine having a body slidable on a mine bottom and having cutting mechanism including a cutter bar pivoted at one end of the machine body and adjustable into longitudinal or lateral positions, of flexible feeding mechanism for feeding said bar into a face and laterally along the same in either direction when said bar is either longitudinally or laterally disposed including a feed 115 operating member disposed on a horizontal axis and at the opposite end of the machine body from the cutter bar pivot.

113. The combination with a mining machine having a body slidable on the mine 125 bottom and having cutting mechanism including a cutter bar pivoted at one end of the machine body and adjustable into longitudinal or lateral positions, of flexible feeding mechanism for feeding said bar into a 130

face and laterally along the same when said bar is either longitudinally or laterally disposed including a feed operating member disposed on a horizontal axis and at the

8 opposite end of the machine body from the cutter bar pivot, said feeding mechanism including flexible feeding means cooperating with said feed operating member and having flexible feeding portions extending in opposite directions from opposite ends of the machine body.

114. The combination with a mining machine having a body slideable on a mine bottom and having cutting mechanism including a cutter bar pivoted at one end of the machine body and adjustable into longitudinal or lateral positions, of flexible feeding mechanism for feeding said bar into a face and laterally along the same in either direction when said bar is either longitudinally or laterally disposed including a feed operating member disposed on a horizontal axis and at the opposite end of the machine body from the cutter bar pivot, said feeding mechanism including flexible feeding means cooperating with said feed operating member and having flexible feeding portions extending in opposite directions from opposite ends of the machine body.

30 115. The combination with a mining machine having a body slideable on the mine bottom and having cutting mechanism including a cutter bar pivoted at one end of the machine body and adjustable into longitudinal or lateral positions, of flexible feeding mechanism for feeding said bar into a face and laterally along the same when said bar is either longitudinally or laterally disposed including a feed operating member disposed on a horizontal axis and at the opposite end of the machine body from the cutter bar pivot, said feeding mechanism including flexible feeding means cooperating with said feed operating member and having flexible feeding portions extending in opposite directions from opposite ends of the machine body, either of said feeding portions being connectible to said bar to swing the same into either its longitudinal 40 or lateral position.

116. The combination with a mining machine having a body slideable on a mine bottom and having cutting mechanism including a cutter bar pivoted at one end of the machine body and adjustable into longitudinal or lateral positions, of flexible feeding mechanism for feeding said bar into a face and laterally along the same in either direction when said bar is either longitudinally or laterally disposed including a feed operating member disposed on a horizontal axis and at the opposite end of the machine body from the cutter bar pivot, said feeding mechanism including flexible feeding means 55 cooperating with said feed operating mem-

ber and having flexible feeding portions extending in opposite directions from opposite ends of the machine body, either of said feeding portions being connectible to said bar to swing the same into either its longitudinal or lateral position.

117. In a mining machine, the combination of a machine body adapted to rest upon and slide over the floor of a mine, of a horizontally extending elongated cutting mechanism pivotally supported on said machine body, means to lock said cutting mechanism in any one of several angular positions relative to said machine body, means to move the machine bodily relative to the coal face including a feed operating member rotatable on a horizontal axis, and flexible feeding means cooperating therewith, said flexible means being connectible to said cutting mechanism to effect swinging thereof about its pivot during the cutting operation, said flexible means having flexible portions extending in opposite directions from opposite ends of the machine body operative to control the angular relation of the machine body with respect to the coal face during either lateral or longitudinal movement of cutting mechanism.

118. In a mining machine, the combination of a machine body adapted to rest upon and slide over the floor of a mine, of a horizontally extending elongated cutting mechanism pivotally mounted on said machine body, means to lock said cutting mechanism in any one of several angular positions relative to the machine body, and means to swing said cutting mechanism about its pivot during the cutting operation, said latter means including feeding mechanism adapted to move the machine bodily relative to the material to be mined, said feeding mechanism also including a feed operating member rotatable on a horizontal axis, and flexible feeding means cooperating therewith, said flexible feeding means having flexible feeding portions extending in opposite directions from opposite ends of the machine body operative to control the angular relation of the machine body relative to the coal face during either lateral or longitudinal movement of said cutting mechanism.

119. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon an axis lying in the same longitudinal vertical plane with the axis of rotation of said pinion, a shaft operatively connected with said feed operating member and rotating on an axis parallel to the axis

of said pinion, and operative connections between said shaft and pinion operative to effect rotation of said shaft at a plurality of predetermined speeds in the same direction including a plurality of gear elements all of which rotate on axes parallel to the axis of said pinion.

120. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon an axis disposed in a vertical longitudinally extending plane, operative connections between said feed operating member and said last mentioned pinion including a pair of shafts rotatable on axes parallel to the axis of said pinion and on opposite sides of a plane including said last axis, gearing for transmitting rotation from one of said shafts 25 to the other at a plurality of speeds in the same direction all of whose elements rotate on axes parallel to that of said second pinion, and means for connecting that one of said parallel shafts which constitutes the driving 30 element to said second pinion.

121. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon 35 an axis disposed in a vertical longitudinally extending plane, and operative connections between said feed operating member and said last mentioned pinion including a pair of shafts rotatable on axes parallel to the axis of said pinion and on opposite sides of a plane including said last axis, gearing for transmitting rotation from one of said shafts to the other at a plurality of speeds in the 40 same direction all of whose elements rotate on axes parallel to that of said second pinion, and means including a gear coaxial with that one of said parallel shafts which constitutes the driving element for connecting the latter directly in driven relation to said second 45 pinion.

122. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon 50 an axis lying in the same longitudinal ver-

tical plane with the axis of rotation of said pinion, a shaft operatively connected with said feed operating member and rotating on an axis parallel to the axis of said pinion, and operative connections between said shaft and pinion operative to effect rotation of said shaft at a plurality of predetermined speeds in the same direction and under frictional control at each speed including a plurality of gear elements all of which rotate 55 on axes parallel to the axis of said pinion.

123. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon 60 an axis lying in the same longitudinal vertical plane with the axis of rotation of said pinion, a shaft operatively connected with said feed operating member and rotating on an axis parallel to the axis of said pinion, and operative connections between said shaft and pinion operative to effect rotation of said shaft at a plurality of predetermined speeds in the same direction and under frictional control at each speed including a friction device operative during power transmission at each speed and a plurality of gear elements all of which rotate on axes 65 parallel to the axis of said pinion.

124. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed operating member adapted to cooperate directly with a flexible feeding element and rotatable upon 70 an axis disposed in a vertical longitudinally extending plane, and operative connections between said feed operating member and said last mentioned pinion including a pair of shafts rotatable on axes parallel to the axis of said pinion and on opposite sides of a plane including said last axis, gearing for transmitting rotation from one of said shafts to the other at a plurality of speeds in the 75 same direction all of whose elements rotate on axes parallel to that of said second pinion, means for effecting frictional control at each 80 speed, and means for connecting that one of said parallel shafts which constitutes the driving element to said second pinion.

125. In a mining machine, a motor having driving pinions at opposite ends thereof, cutting mechanism at one end of said motor including a pivoted cutter bar having a circulating cutter chain driven from one of said pinions, and feeding mechanism driven by said other pinion including a feed oper- 85

- ating member adapted to cooperate directly with a flexible feeding element and rotatable upon an axis disposed in a vertical longitudinally extending plane, and operative connections between said feed operating member and said last mentioned pinion including a pair of shafts rotatable on axes parallel to the axis of said pinion and on opposite sides of a plane including said last axis, 5 gearing for transmitting rotation from one of said shafts to the other at a plurality of speeds in the same direction all of whose elements rotate on axes parallel to that of said second pinion, means operative at each of 10 said speeds to effect frictional control, and means including a gear coaxial with that one of said parallel shafts which constitutes the driving element for connecting the latter directly in driven relation to said second pinion.
126. In a mining apparatus, a motor, cutting mechanism driven thereby including a pivoted cutter bar having a circulating cutter chain to which circulating movement is 15 transmitted from one end of said motor, and feeding means driven from the other end of said motor including a rotatable feed operating member adapted to cooperate directly with a flexible feeding element during feed, 20 a power transmitting member rotating on an axis parallel with the axis of said feed operating member and constituting a driving element for said feed operating member, means for rotating said power transmitting member including a shaft coaxial therewith, a plurality of driving members for said shaft coaxial with and surrounding the latter and selectively connectible thereto to effect rotation 25 thereof at different predetermined speeds, and means for selectively effecting such connection.
127. In a mining apparatus, a motor, cutting mechanism driven thereby including a pivoted cutter bar having a circulating cutter chain to which circulating movement is 30 transmitted from one end of said motor, and feeding means driven from the other end of said motor including a rotatable feed operating member adapted to cooperate directly with a flexible feeding element during feed, 35 a power transmitting member rotating on an axis parallel with the axis of said feed operating member and constituting a driving element for said feed operating member, means for rotating said power transmitting member including a shaft coaxial therewith, a plurality of driving members for said shaft coaxial with and surrounding the latter and selectively connectible thereto to effect rotation 40 thereof at different predetermined speeds, and means for selectively effecting such connection.
128. In a mining apparatus, a motor, cutting mechanism driven thereby including a pivoted cutter bar having a circulating cutter chain to which circulating movement is 45 transmitted from one end of said motor, and feeding means driven from the other end of said motor including a rotatable feed operating member adapted to cooperate directly with a flexible feeding element during feed, 50 a power transmitting member rotating on an axis parallel with the axis of said feed operating member and constituting a driving element for said feed operating member, means for rotating said power transmitting member including a shaft coaxial therewith, a plurality of driving members for said shaft coaxial with and surrounding the latter and selectively connectible thereto to effect rotation 55 thereof at different predetermined speeds, and friction clutch means coaxial with said shaft for selectively effecting such connection.
129. In a mining apparatus, a motor, cutting mechanism driven thereby including a pivoted cutter bar having a circulating cutter chain about which circulating movement is 60 transmitted from one end of said motor, and feeding means driven from the other end of said motor including a feed operating member rotatable on an axis disposed in a vertical plane extending longitudinally of said apparatus adapted to cooperate directly with a flexible feeding element during feed, 65 a power transmitting member rotating on an axis parallel with the axis of said feed operating member and constituting a driving element for said feed operating member, and means for rotating said power transmitting member including a shaft coaxial therewith, a plurality of driving members for said shaft coaxial with and surrounding the latter and selectively connectible thereto to effect rotation 70 thereof at different predetermined speeds, and separate friction clutch means coaxial with said shaft and oppositely movable to effect such selective connection.
130. In a mining apparatus, a motor, cutting mechanism driven thereby including a pivoted cutter bar having a circulating cutter chain about which circulating movement is 75 transmitted from one end of said motor, and feeding means driven from the other end of said motor including a feed operating member rotatable on an axis disposed in a vertical plane extending longitudinally of said apparatus adapted to cooperate directly with a flexible feeding element during feed, 80 a power transmitting member rotating on an axis parallel with the axis of said feed operating member and constituting a driving element for said feed operating member, and means for rotating said power transmitting member including a shaft coaxial therewith, a plurality of driving members for said shaft coaxial with and surrounding the latter and selectively connectible thereto to effect rotation 85 thereof at different predetermined speeds, and separate friction clutch means coaxial with said shaft and oppositely movable to effect such selective connection.
131. In a mining apparatus, a motor, cutting mechanism driven thereby including a pivoted cutter bar having a circulating cutter chain about which circulating movement is 90 transmitted from one end of said motor, and feeding means driven from the other end of said motor including a feed operating member rotatable on an axis disposed in a vertical plane extending longitudinally of said apparatus adapted to cooperate directly with a flexible feeding element during feed, 95 a power transmitting member rotating on an axis parallel with the axis of said feed operating member and constituting a driving element for said feed operating member, and means for rotating said power transmitting member including a shaft coaxial therewith, a plurality of driving members for said shaft coaxial with and surrounding the latter and selectively connectible thereto to effect rotation 100 thereof at different predetermined speeds, and separate friction clutch means coaxial with said shaft and oppositely movable to effect such selective connection.
132. In a mining apparatus, a motor, cutting mechanism driven thereby including a pivoted cutter bar having a circulating cutter chain about which circulating movement is 105 transmitted from one end of said motor, and feeding means driven from the other end of said motor including a feed operating member rotatable on an axis disposed in a vertical plane extending longitudinally of said apparatus adapted to cooperate directly with a flexible feeding element during feed, 110 a power transmitting member rotating on an axis parallel with the axis of said feed operating member and constituting a driving element for said feed operating member, and means for rotating said power transmitting member including a shaft coaxial therewith, a plurality of driving members for said shaft coaxial with and surrounding the latter and selectively connectible thereto to effect rotation 115 thereof at different predetermined speeds, and separate friction clutch means coaxial with said shaft and oppositely movable to effect such selective connection.
133. In a mining apparatus, a motor, cutting mechanism driven thereby including a pivoted cutter bar having a circulating cutter chain about which circulating movement is 120 transmitted from one end of said motor, and feeding means driven from the other end of said motor including a feed operating member rotatable on an axis disposed in a vertical plane extending longitudinally of said apparatus adapted to cooperate directly with a flexible feeding element during feed, 125 a power transmitting member rotating on an axis parallel with the axis of said feed operating member and constituting a driving element for said feed operating member, and means for rotating said power transmitting member including a shaft coaxial therewith, a plurality of driving members for said shaft coaxial with and surrounding the latter and selectively connectible thereto to effect rotation 130 thereof at different predetermined speeds, and separate friction clutch means coaxial with said shaft and oppositely movable to effect such selective connection.

terminated speeds, and clutch means coaxial with said shaft for selectively effecting such connection.

131. In a mining apparatus, a motor, cutting mechanism driven thereby including a pivoted cutter bar having a circulating cutter chain about which circulating movement is transmitted from one end of said motor, and feeding means driven from the other 10 end of said motor including a feed operating member rotatable on an axis disposed in a vertical plane extending longitudinally of said apparatus adapted to cooperate directly with a flexible feeding element during feed, 15 a power transmitting member rotating on an axis parallel with the axis of said feed operating member and constituting a driving element for said feed operating member, and means for rotating said power transmitting member including a shaft coaxial therewith, a plurality of driving members for said shaft coaxial with the latter and selectively connectible thereto to effect rotation thereof at different predetermined 20 speeds, and clutch means coaxial with said shaft and oppositely movable relative thereto for selectively effecting such connection.
132. In a mining apparatus, a motor, cutting mechanism driven thereby including a 30 pivoted cutter bar having a circulating cutter chain to which circulating movement is transmitted from one end of said motor, and feeding means driven from the other end of said motor including a rotatable feed operating member adapted to cooperate directly with a flexible feeding element during feed, 35

a power transmitting member rotating on an axis parallel with the axis of said feed operating member fixed against longitudinal movement and constituting a driving element for said feed operating member, means for rotating said power transmitting member including a plurality of driving members coaxial therewith and selectively connectible thereto to effect rotation thereof 40 at different predetermined speeds, and means for selectively effecting such connection. 45

133. In a mining apparatus, a motor, cutting mechanism driven thereby including a pivoted cutter bar having a circulating cutter chain to which circulating movement is transmitted from one end of said motor, and feeding means driven from the other end of said motor including a rotatable feed operating member adapted to cooperate directly 50 with a flexible feeding element during feed, a power transmitting member rotating on an axis parallel with the axis of said feed operating member and constituting a driving element for said feed operating member, means for rotating said power transmitting member including a shaft fixed thereto and coaxial therewith, a plurality of driving members for said shaft coaxial with and surrounding the latter and selectively connectible thereto to effect rotation thereof at different predetermined 55 speeds, and friction clutch means for selectively effecting such connection. 60

In testimony whereof I affix my signature.

MORRIS P. HOLMES.

CERTIFICATE OF CORRECTION.

Patent No. 1,662,788.

Granted March 13, 1928, to

MORRIS P. HOLMES.

It is hereby certified that error appears in the printed specification of the above numbered patent requiring correction as follows: Page 2, line 73, for the word "alternately" read "alternatively"; page 4, line 103, for the misspelled word "spocket" read "sprocket", and page 8, line 7, claim 19, for "lognitudinally" read "longitudinally"; and that the said Letters Patent should be read with these corrections therein that the same may conform to the record of the case in the Patent Office.

Signed and sealed this 10th day of April, A. D. 1928.

(Seal)

M. J. Moore,
Acting Commissioner of Patents.
